UNITED STATES PATENT OFFICE.

ARTHUR CLAYTON AND GEORGE W. BRITNER, OF SAN FRANCISCO, CALIFORNIA; SAID BRITNER ASSIGNOR OF ONE-HALF OF HIS ENTIRE RIGHT TO SAID CLAYTON AND ONE-HALF OF HIS ENTIRE RIGHT TO AMANDA HANFORD AGOSTINI, OF BERKELEY, CALIFORNIA.

BILLIARD CUE.

Application filed November 28, 1921. Serial No. 518,238.

To all whom it may concern:

Be it known that we, ARTHUR CLAYTON and GEORGE W. BRITNER, citizens of the United States, residing at San Francisco, county of San Francisco, State of California, have invented certain new and useful Improvements in Billiard Cues; and we do declare the following to be a full, clear, and exact description of the same, reference being had to the accompanying drawings, and to the characters of reference marked thereon, which form a part of this application.

This invention relates to improvements in cues such as are used in playing billiards or pool; the principal object of the invention being to provide a cue constructed in such a manner that the player cannot lose his stroke or aim against the ball by placing the weight of the body on the cue or gripping the same too tightly with the hand used to make the stroke or impart the necessary movement to the cue.

Relaxation and not tenseness of the muscles is the aim of good players and is necessary, with the present style of cues, in order to insure good "shots." This same effect however is gained by the use of our improved cue, even without the desirable but sometimes hard to attain relaxation of the muscles as will be evident hereinafter.

A further object of the invention is to produce a simple and inexpensive device and yet one which will be exceedingly effective for the purposes for which it is designed.

These objects we accomplish by means of such structure and relative arrangement of parts as will fully appear by a perusal of the following specification and claims.

In the drawings similar characters of reference indicate corresponding parts in the several views:

Fig. 1 is a side view of our improved cue.

Fig. 2 is an enlarged partial section thereof.

Referring now more particularly to the characters of reference on the drawings, the numeral 1 denotes the outer or tip end of the cue, secured in the usual manner to the rear portion 2, these portions together being practically one, and whose total

length is that of the complete cue, which increases in diameter from tip to butt, as 55 is customary.

A certain distance from its connection with the member 1 the member 2 is reduced in diameter to form a cylindrical portion 3, having a constant diameter throughout, and which extends to the rear end or butt of the cue, on which portion is turnably mounted a sleeve 4, this sleeve being of the length necessary to form the handle portion and having its outer periphery continuous with the outer surface of the main member 2.

To prevent undesired removal of the sleeve, a butt-plate 5 is provided at the rear end of the same which is provided 70 with a polygonal-sided projection 6 which is socketed into the adjacent end of the portion 3, so that the butt-plate cannot turn. This plate in turn is held in position by means of a screw 7 which passes through 75 the plate and into the portion 3, or by any other suitable means, the plate and member 3 abutting against each other so that tightening of the screw cannot pinch 80 the sleeve.

Rubber or similar gaskets or washers 8 are placed between the butt plate and the sleeve, and between the latter and the shoulder formed by and between the portions 2 and 3.

In operation then, no matter how hard the handle-sleeve may be gripped by a novice or a nervous player, the tensional strain induced by such grip is removed from the main portion of the cue itself, thus allowing for the stroke to be free and as aimed at the ball.

This same principle of construction may also be applied to fountain pens and other articles whose users are accustomed to grip 95 them with sufficient tenseness to spoil the efficient operation of the implement.

From the foregoing description it will be readily seen that we have produced such a device as substantially fulfills the objects of the invention as set forth herein.

While this specification sets forth in detail the present and preferred construction of the device, still in practice such deviations from such detail may be resorted to 105 as do not form a departure from the spirit

of the invention, as defined by the appended claims.

Having thus described our invention, what we claim as new and useful and desire to secure by Letters Patent is:

- 5 1. A billiard cue comprising a main cue member having a reduced portion at one end, a handle turnably mounted on the reduced portion, and a butt plate of greater diameter secured to and abutted against the outer end of said reduced portion, the latter being of greater length than the handle whereby the butt plate cannot be advanced into frictional engagement with the handle.
- 10 2. A billiard cue comprising a main cue portion having a reduced portion at one end, a handle turnably mounted on said reduced portion, the latter extending beyond the outer end of the handle, a butt plate of greater diameter than said reduced portion abutting against the outer end of the latter, means formed with the reduced portion and plate for preventing rotation of the latter, and means for removably holding the plate in position.
- 15 3. A billiard cue comprising a main cue portion having a reduced portion at one end,

a handle turnably mounted on said reduced portion, the latter extending beyond the outer end of the handle, a butt plate of greater diameter than the reduced portion abutting against the outer end of the latter, a flat sided projection extending from the inner end of said plate and adapted to seat in a recess provided in the outer end of the reduced portion and a screw projecting through the plate and into said reduced portion of the cue.

4. A billiard cue comprising a main member reduced in size at one end, a handle turnably mounted on the reduced portion; a butt plate of greater diameter than the latter positioned at the outer end thereof, a flat sided projection extending from the plate into a recess provided in the outer end of the reduced portion, a screw holding said plate to the cue, and means then preventing pinching of the handle between the plate and main cue portion.

In testimony whereof we affix our signatures.

ARTHUR CLAYTON.
GEORGE W. BRITNER,
